Inventor
Edward W. Mooring

By *Ch. Harten* Attorney

UNITED STATES PATENT OFFICE.

EDWARD W. MOORING, OF CASPER, WYOMING.

BURNER.

Application filed March 28, 1924. Serial No. 702,669.

To all whom it may concern:

Be it known that I, EDWARD W. MOORING, a citizen of the United States, residing at Casper, in the county of Natrona and State of Wyoming, have invented certain new and useful Improvements in Burners, of which the following is a specification.

This invention relates to burners, and more particularly to gas burners.

10 An object of the invention is to provide a gas burner designed for use with either high or low pressure gas and with artificial or natural gas.

15 A further object of the invention is the provision of a burner adapted to be used in domestic boilers, furnaces, or any type of heating plant.

20 A further object is the provision of a burner of simple construction that is efficient in operation.

25 In the accompanying drawings, I have shown one embodiment of the invention. In this showing:

Figure 1 is a side elevation of the burner assembly, the burner per se being shown in section,

Figure 2 is an end elevation,

Figure 3 is a detail sectional view on line 3—3 of Figure 2, and,

30 Figure 4 is a perspective view of an adjusting disk.

The burner is adapted to be arranged in the ash pit or fuel door of an ordinary boiler or furnace, and consists of a valve 35 casing 1, having a valve (not shown) arranged therein and controlled by a valve stem 2 projecting from the casing. A section of pipe 3 is connected to the valve casing and the burner head 4 is connected to this section of pipe by means of a coupling

40 5. The end of the burner is provided with a pair of pipes 6 welded or fashioned into a cross. The burner is surrounded by an open ended cylinder 7, with the cross pipes 45 6 arranged at one end of the cylinder. These pipes are provided with a plurality of perforations 8, arranged at an angle of from 45° to 60° to produce a whirling effect in the gas flame.

50 A disk 9 is arranged on the pipe 3 ad-

jacent the rear end of the cylinder. As shown, the disk is provided with a sleeve 10 having a set screw 11 by means of which it may be adjusted longitudinally of the pipe.

55 In operation, air is drawn through the cylinder 7 and mixed with the gas issuing from the openings 8 in the cross pipes. Due to the angles of the perforations, the gas is given a whirling effect and more air is drawn into the burner and consumed. The flow of air is automatically regulated by the suction of the gas and the proper amount of air to support combustion is obtained. The flow of gas is regulated by the valve 60 in the valve casing 1. The disk 9 is employed merely for the purpose of minute adjustment and may be regulated by loosening the set screw 11 and adjusting it on the pipe 3. The burner differs from the usual 65 construction of burner in that no interior mixing chamber is provided and an excess of air is employed, causing practically a 70 blast flame.

75 It is to be understood that the form of my invention herewith shown and described is to be taken as a preferred example of the same, and that various changes in the shape, size, and arrangement of parts may be resorted to without departing from the spirit 80 of the invention or the scope of the subjoined claims.

I claim:

1. A gas burner comprising an inlet pipe, 85 a pair of crossed pipes arranged on the end of said inlet pipe, said crossed pipes being provided with perforations, said perforations being arranged at an angle to the axes of said pipes, a cylinder surrounding said pipes and means for controlling the 90 admission of air to said cylinder.

2. A gas burner comprising an inlet pipe, 95 a pair of crossed pipes arranged on the end of said inlet pipe, said crossed pipes being provided with perforations, a cylinder surrounding said pipes, and a disk arranged on said inlet pipe adjacent the end of said cylinder.

3. A gas burner comprising an inlet pipe, 100 a pair of crossed pipes arranged on the end

of said inlet pipe, and a cylinder surrounding said pipe, said crossed pipes being provided with perforations extending radially of said cylinder and arranged at an angle to deliver flame outwardly toward the exterior of said cylinder and away from the adjacent crossed pipe.

In testimony whereof, I affix my signature in presence of two witnesses.

EDWARD W. MOORING.
